VACUUM CLEANER

Dewey M. Dow, Toledo, Ohio, assignor to Air-Way Electric Appliance Corporation, Toledo, Ohio, a corporation of Delaware

Application October 3, 1936, Serial No. 103,882

2 Claims. (Cl. 15—16)

This invention relates to vacuum cleaners of a type in which the axes of fan and motor are separated, parallel, and horizontal and in which the fan is driven by a belt or belts travelling over pulleys on the fan and motor shafts respectively, and the object of the invention is to provide such an arrangement in which the motor is vibration insulated from the body of the cleaner and from the fan casing, and yet is mounted sturdily enough to resist the pull of the belt or belts and remain in proper alignment.

The invention further aims to provide a compact arrangement of the motor relative to the suction chamber casting of the cleaner, on which the motor is mounted.

Further objects will appear in the perusal of the following detailed description of the invention in connection with the accompanying drawing in which:

Fig. 1 is a plan view of a vacuum cleaner embodying the invention, parts being broken away to better illustrate the construction.

Fig. 2 is a side elevation of the same, the suction chamber being shown in section.

Fig. 3 is a transverse vertical sectional view showing the motor and its mounting.

Fig. 4 is a sectional view taken on the line 4—4 of Fig. 2.

Fig. 5 is a perspective view of one of the mounting devices, and

Fig. 6 is an end view of the motor with mounting device attached.

A cleaner constructed according to my invention comprises a suction chamber 10 formed at its forward extremity with an agitator chamber 11 and at its rear extremity with a throat 12, bifurcated in its rear region and attached to a pair of elbows 13, projecting upwardly and rearwardly. A fan casing 14 has its inlets swivelled between the outlets of the elbows 13 and the fan impeller (not shown) is mounted on a shaft 15 journalled in the elbows 13.

The upper wall 16 of the suction chamber 10 is formed with a downwardly curved depression 17, defined by a ridge 18 cast in the wall 16. The depression 17 is located rearwardly of the agitator chamber 11 and forwardly of the fan casing 14. It is made as deep as is consistent with leaving ample space in the throat 12 for free flow of air therethrough.

The depression 17 is defined at its ends by cross ridges 20, each formed with a pair of bosses 21. The motor 19 is mounted upon a pair of mounting devices M each of which comprises an angle bracket 22, seated upon the cross ridge 20 and

secured by screws 23 threaded into the bosses 21, an arcuate metal plate 24, one side of which is welded to the vertical leg of the angle bracket 22, an arcuate block 25 of soft rubber vulcanized to the other side of the plate 24, and a second arcuate plate 26, vulcanized to the other side of the rubber block 25. The plate 26 is secured to the end wall 27 (Fig. 4) of the motor 19 by means of screws 28 extending through openings 29 in the plate 24 and rubber 25, and openings in the plate 26. The latter openings are just large enough to receive the threaded portions of the screws, the openings 29 being large enough to receive the heads.

The mounting devices M are slightly less than 15 a semi-circle in arcuate length, and are positioned with their rear ends higher than their forward ends, so that their greatest length is substantially parallel to the belts 30 connecting the fan shaft 15 to the motor shaft 31, roughly parallel to the belt 32 connecting the shaft 31 to the rotary agitator 33, but not as much so as it is with relation to the belts 30 which exert the greatest pull upon the motor.

The mounting devices M, being substantially 25 semi-cylindrical, and attached to the motor concentrically with respect to the shaft 31, give maximum resistance to torque forces and the linear forces of belt pull, with a minimum area of rubber. They embrace the bearing caps 33 of the 30 shaft 31 so as to occupy a minimum of space.

The angle brackets 22 are arranged so that the full thickness of the mounting devices M is received inside the cross ridges 20 yet the horizontal legs of the brackets project beyond the ridges 20 to give ample space for the reception of the screws 23. The use of vertically removable screws enables the motor and mounting devices to be detached and lifted out as a unit and makes the screws very accessible.

On one side of the cleaner, a partition wall 34 is positioned directly over the cross ridge 20, its lower edge engaging the upper edge of the ridge. A motor cover 35 and a belt housing bottom plate 36 together coat with the partition 34 to seal 45 off the belt 32 from the motor space under the cover 35, so that there will be no loss of suction through the opening 37, which allows the belt 32 to enter the agitator chamber. The partition wall 34 has a flange 38 formed on its lower edge 50 for a portion of its length and the screws 23 secure the flange 38 as well as the bracket 22.

I am aware that rubber sandwich mountings are old in many forms and that such mountings have been used at the ends of a motor to absorb 55

all types of strain including torsional. The present invention, however, constitutes an improvement in arrangement of such a mounting in a vacuum cleaner of the type herein described, and in the construction of the mounting so that it is adaptable to such arrangement.

5 I claim as my invention:

1. In a vacuum cleaner, a floor tool comprising an agitator chamber with an exhaust throat therefor having a depression formed in the upper wall of the throat for receiving an electric motor and a pair of ridges in said upper wall defining the ends of the depression, means for mounting said motor comprising a pair of mounting devices each including an arcuate metal plate secured to a respective end of the motor, an arcuate body of rubber vulcanized to said plate, a second arcuate plate of metal vulcanized to said body of rubber, and an angle bracket secured to 10 said second plate, said bracket including a leg projecting at right angles from said second plate,

intermediate the upper and lower extremities thereof, and resting upon the portions of the suction chamber defining the ends of said depression, and means securing said legs to the suction chamber, the lower regions of said motor and of said mounting devices projecting into said depression.

2. In a vacuum cleaner, a suction chamber formed with upwardly projecting bosses with an electric motor disposed therebetween, and a pair of mounting devices each including an arcuate metal plate secured to a respective end of the motor, an arcuate body of rubber vulcanized to said plate, a second arcuate plate of metal vulcanized to said body of rubber, and a bracket member 15 projecting at right angles from said second plate, intermediate the upper and lower extremities thereof, and resting upon the said bosses, and means securing said bracket members to the said bosses.

20 DEWEY M. DOW.
